CLEANING IMPLEMENT

Arthur J. Knott, Natick, Mass.

Application February 27, 1934, Serial No. 713,108

4 Claims. (Cl. 15—144)

My invention relates to a cleaning implement and more especially to an arrangement for attaching a handle, or the like, to a frame associated with the pad of an applicator, polisher, mop or similar tool.

The usual wax applicator, polisher or mop consists, generally speaking, of a head and a handle, the head comprising a frame to which a pad or the like is attached and the handle which is usually an elongated wooden rod, having a connector on one of its ends, the connector being secured in some manner on the frame. In order that the angle of the handle, with respect to the head, may be varied to suit different operating conditions, it has been proposed, in some instances, to provide a connector having a pivotal engagement with the frame, some form of clamping device serving to hold the handle in the desired position, usually by friction.

I have found that, with certain types of work, it is desirable to have the applicator or mop head free to swing on the handle while, with other types of work, it is better to have the head rigid with respect to the handle, the latter being at an angle with respect to the head. The principal object of the present invention is to bring about a form of applicator, polisher or mop which may be adapted more readily, than heretofore possible, to the various working conditions under which these devices are used.

In a more specific aspect it is an object of the invention to bring about a form of wax applicator, polisher or mop which may be adjusted so that the head may have either a more or less free swinging movement, with respect to the handle, or so that the handle is rigidly secured against movement with respect to the head, the handle being preferably at an angle to the head.

A feature of the invention resides in a form of cleaning implement head and handle connector which may be adjusted so as to be rigidly held or locked against movement with respect to one another and in which the use of frictional contacts, for this purpose, is entirely eliminated.

A further feature of the invention resides in a form of cleaning implement frame, and handle connector associated therewith, which may be formed entirely out of sheet material.

In carrying out the invention I propose to make use of a cylindrical pivot member, associated with the cleaning implement frame and forming a seat for the handle connector, the axis of the cylindrical pivot member being at right angles to the handle axis. A still further

feature of the invention resides in a pivot member which is an integral part of the sheet metal frame and which is shaped, at least in part, to form a cylindrical connector seat.

To these and other ends, the invention consists in the novel features and combinations of parts to be hereinafter described and claimed.

In the drawing:

Fig. 1 is a plan view, on a reduced scale, of a wax applicator embodying the invention.

Fig. 2 is a sectional view taken along line 2—2 of Fig. 1, but on an enlarged scale;

Fig. 3 is a view similar to Fig. 2 but showing the applicator handle in a different position;

Fig. 4 is a sectional view taken along line 4—4 of Fig. 1, but on an enlarged scale, and

Fig. 5 is a sectional view taken along line 5—5 of Fig. 3.

Referring now to the drawings in which I have illustrated my invention by showing a preferred embodiment of the same, the reference numeral 10 indicates, in general, the frame of a wax applicator head, or the like, the frame, in this instance, taking the form of a pair of co-operating sheet metal plates 11 and 12, between which a pad 13, of sheep-skin or other suitable material, is clamped. The plates 11 and 12 are pressed into channel form, the upper plate 11 being somewhat narrower than the lower plate 12 and having downwardly directed flanges 14 and 15, on two of its opposite side edges, the flanges 14 and 15 being received between the upwardly directed flanges 16 and 17, on the side edges of plate 12. The inner ends of the sheep-skin pad are clamped between the lower ends of flanges 14 and 15, the pad extending around the flanges 16 and 17 and the under side of plate 12. Bolts or other suitable means 18 clamp the plates 11 and 12 together and thus hold the pad 13 securely on the applicator frame.

Two longitudinally directed slits are formed in plate 11, the slits being spaced from one another and parallel to the side edges of the plate. The material of the plate 11, between the slits, is pressed upwardly to form an elongated arched rib 19, the rib being midway between the side edges of plate 11 and midway between the ends thereof. The rib 19 is folded around a cylindrical rod 20, to form a cylindrical handle connector seat, the axis of the seat being spaced from the upper face of plate 11 and parallel to the side edges thereof. The ends 21 and 22, of rib 19, are substantially flat, where the rib merges into the plate 11, but are of arcuate cross-sectional shape towards the handle seat, the radius of

curvature decreasing towards the seat until, adjacent to the seat, the radius of curvature is the same as that of the seat. The folding of the material of the rib 19, around rod 20, leaves openings 23 and 24, in plate 11, on the opposite sides of rib 19, the opening 23 being relatively narrow while the opening 24 is relatively wider. The additional width, given to opening 24, may be obtained by removing the necessary part of the plate either during or after the formation of rib 19. The edges 25 and 26, of openings 23 and 24, are parallel to the side edges of plate 11, as shown in Fig. 1.

On the inner end of handle 27, which may be of any desired length, is a handle connector 28, made out of two somewhat similar sheet metal stampings 29 and 30, each of which has a hollow semi-cylindrical end, as at 31 and 32, the inner end of handle 27 being received within the ends 31 and 32. Near their opposite ends the connector parts 29 and 30 are arched, as at 33 and 34, to form co-operating transverse grooves 35 and 36, within which the cylindrical seat of rib 19 is received. The arched portions 33 and 34, of the connector parts 29 and 30, are joined to the semi-cylindrical parts 31 and 32 by webs 37, 38, 39 and 40 and conical extensions 41 and 42, the webs being flat and in planes parallel to the plane defined by the axes of the handle and handle connector seat. Beyond the arched portions 33 and 34 the connector parts 29 and 30 terminate in jaws 43 and 44, jaw 43 being bent outwardly while jaw 44 is bent inwardly, the jaws co-operating in a manner to be hereinafter described. A bolt 45 passes through the connector parts 29 and 30 and serves to clamp the same on the handle 27 and rib 19. A winged nut 46 forms a convenient means for adjusting the pressure exerted on the handle and rib.

The operation of the applicator is relatively simple. If the conditions, under which it is being used, are such that it is desirable to have the head capable of swinging on the handle, the handle connector is assembled on its seat in the position shown in Figs. 1 and 2. In this position the cylindrical portion of the rib 19 is received in grooves 35 and 36, the jaws 43 and 44 extending into opening 24. The width of opening 24 is such as to provide clearance for the jaws 43 and 44, the handle connector, and thus the handle, swinging on the cylindrical portion of the rib 19, subject to the frictional resistance of the rib 19 in the grooves which may be varied by tightening or loosening the winged nut 46 on bolt 45.

If the conditions, under which the applicator is being used, are such that it is desirable to have the handle rigidly connected to the head, the nut 46 is loosened sufficiently for the connector to be withdrawn from the rib 19, whereupon the connector is reversed on the frame into the position shown in Fig. 3, the connector being reassembled on the frame with the rib 19 in grooves 35 and 36, the plate 11 passing between the jaws 43 and 44. The opening 23 provides clearance for the jaw 44 to pass under the plate 11, the edge 25 of opening 23 being at such a distance from the rib 19 that the jaws may grip the plate 11 over a substantial area. The nut 46 is now tightened sufficiently for the jaws 43 and 44 to grip the plate 11, and the arched portions 33 and 34 to grip the rib 19, whereupon the handle connector and handle are rigidly connected to the head at an angle depending on the angle of the

jaws 43 and 44 with respect to the handle axis. An angle of 45° will be found highly desirable for most working conditions although this angle may be varied if desired. It will be noted, especially from Figs. 2, 3 and 5, that sufficient clearance is provided between the connector parts 29 and 30 so that they will not come in contact as the nut 46 is tightened.

It will be readily understood, from the above description of the invention, that the construction of the applicator is such that the manufacturing operations are almost entirely limited to press work, the amount of assembly work being reduced to a minimum. The usual bolts, screws or rivets, forming the seat for the handle connector, have been eliminated, the seat provided, not only being more rigid than the usual seat, but being an integral and permanent part of the head frame and not subject to becoming loosened or lost.

While the head may be assembled on the handle so as to swing thereon and the swinging movement may be controlled by varying the frictional resistance of the handle connector on its seat, no dependance is placed on such frictional contact for holding the handle when it is desired to hold the head in a fixed position with respect to the handle, the relation of the handle connector to the frame being such that these parts may be locked rigidly together when desired.

While I have shown and described my invention in connection with a wax applicator, it will be readily understood that it is not limited in its application thereto, accordingly while I have shown and described a preferred embodiment of my invention, it will be understood that it is not to be limited to the details shown, but is capable of modification and variation within the spirit of the invention and the scope of the appended claims.

What I claim is:

1. In a cleaning implement, a head including a relatively flat frame normally parallel to the surface to be cleaned, a handle, a handle connector, a pivot element on the frame having an axis substantially parallel to the frame, said connector being received in either of two positions on the pivot element, gripping means on the end of the connector, means on the frame at one side of the pivot element adapted to be engaged and gripped by said gripping means when the connector is received on the pivot element in one of the positions and an opening in the frame on the other side of the pivot element providing clearance for said gripping means when the connector is received on the pivot element in the other of the positions, the connector being swingable on the pivot element in the second of the positions.

2. In a cleaning implement, a head including a sheet metal frame having a part thereof normally parallel to the surface to be cleaned, a pivot element on the frame having an axis substantially parallel to the part of the frame, there being openings in the frame at either side of the pivot element, one of the openings being of greater width than the other transversely of the pivot axis, a handle, a handle connector on the handle, said handle connector being adapted to be assembled on the pivot element in either of two positions, and means on the connector adapted to engage the frame at the edge of the opening of least width to hold the connector against pivotal movement on the pivot element when the connector is received thereon in one of the posi-

tions, the opening of greater width providing clearance for said means when the connector is received on the seat in the other position.

3. In a cleaning implement, a frame, a pivot element on the frame having an axis normally parallel to the surface to be cleaned, a handle, a handle connector, said handle connector having transverse opposing grooves near its ends in which the pivot element may be received, and cooperating jaws beyond the grooves, said connector being adapted to be received on the pivot element in either of two positions, and means on the frame which is received and gripped between the jaws in one of the positions to hold the connector against pivotal movement on the pivot element, said frame having an opening therein providing clearance for the jaws when the connector is received on the pivot element in the other of the positions, the connector being

free to swing on the pivot element in the last named position.

4. In a cleaning implement, a frame, a pivot element on the frame having an axis normally parallel to the surface to be cleaned, a handle, a handle connector, means on the end of the connector forming a groove which opens towards the connector end, said connector being received in either of two positions on the pivot element, and means on the frame at one side of the pivot element which extends into the groove to hold the connector against movement on the pivot element when the connector is received thereon in one of the positions, the frame being shaped to provide clearance for the end of the connector when the connector is received on the pivot element in the other position, the connector being free to swing on the pivot when received thereon in the latter position.
